Primary Examiner — Catherine R Oliver-Garcia(57) **CLAIM**

The ornamental design for a belt shelf, as shown and described.

DESCRIPTION

FIG. 1 is a top isometric view of a belt shelf showing my new design;

FIG. 2 is a top isometric view shown in use;

FIG. 3 is front elevational view thereof;

FIG. 4 is a rear elevational view thereof;

FIG. 5 is a left side view thereof;

FIG. 6 is a right side view thereof;

FIG. 7 is a top view thereof; and,

FIG. 8 is a bottom view thereof.

The broken line showing of environment is included for the purpose of illustrating only and forms no part of the claimed design.
